US0D1106072S

(12) **United States Design Patent** (10) **Patent No.:** **US D1,106,072 S**
(45) **Date of Patent:** **** Dec. 16, 2025**

(54) **BATTERY PACK CONNECTOR**

(71) Applicant: **BRIGGS & STRATTON, LLC**,
Wauwatosa, WI (US)

(72) Inventors: **John Schneiker**, Muskego, WI (US);
James M. Busse, Kenosha, WI (US);
Ross Eernisse, Wauwatosa, WI (US);
Nick Zeidler, Brookfield, WI (US)

(73) Assignee: **Briggs & Stratton, LLC**, Wauwatosa,
WI (US)

(**) Term: **15 Years**

(21) Appl. No.: **29/884,298**

(22) Filed: **Feb. 9, 2023**

(51) LOC (15) Cl. **13-02**

(57) **CLAIM**

The ornamental design for a battery pack connector as shown and described.

DESCRIPTION

FIG. 1 is a top, front, right perspective view of the claimed design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1;

FIG. 7 is a bottom view of FIG. 1;

FIG. 8 is a bottom, front, right perspective view of FIG. 1;

FIG. 9 is an enlarged view of area 9 as shown in FIG. 7; and,

FIG. 10 is an enlarged view of area 10 as shown in FIG. 8.

The dash-dash broken lines show portions of the article that form no part of the claimed design. The dash-dot broken lines show the bounds of the claim and form no part of the claimed design. The long dash-short dash broken lines illustrate the bounds around the enlarged views and forms no part of the claimed design.
